CLAIM

The ornamental design for a hammer drill, as shown and described.

DESCRIPTION

FIG. 1 is a front perspective view of a hammer drill showing my new design;

FIG. 2 is a side view thereof;

FIG. 3 is the opposite side view of FIG. 2 thereof;

FIG. 4 is a front view thereof;

FIG. 5 is a rear view thereof;

FIG. 6 is a top view thereof; and

FIG. 7 is a bottom view thereof;

FIG. 8 is an alternate embodiment of my new design showing the hammer drill without any writing or logo thereon, but otherwise identical to my first embodiment thereof;

FIG. 9 is a side view thereof;

FIG. 10 is the opposite side view of FIG. 9 thereof;

FIG. 11 is a front view thereof;

FIG. 12 is a rear view thereof;

FIG. 13 is a top view thereof; and,

FIG. 14 is a bottom view thereof.

The broken line showing of environmental structure is for illustrative purposes only, and forms no part of the claimed design.

The names Bosch and Boschhammer displayed on the hammer drill are trademarks owned by Robert Bosch GmbH.
